SHOULDER PAD

Joseph Martone, Forest Hills, N. Y., assignor to
Dale A. Bauer, Tuckahoe, N. Y.

Application April 29, 1947, Serial No. 744,591

6 Claims. (Cl. 2—268)

1

This invention relates to shoulder pads for garments. It has heretofore been proposed to make shoulder pads for garments to change the shoulder line in accordance with style or to correct some imperfect line of the figure. Nevertheless, such shoulder pads have had the general imperfection that the new line is obviously artificial, ungraceful, and has an unfortunate psychological reaction on those who view it. Their artificiality is offensive to many people.

An object of this invention is to make a shoulder pad that, when applied, changes the shoulder line of the garment but makes a new shoulder line of natural appearance and conformity, and gives to the garment a natural drape.

One of the disadvantages of prior art shoulder pads has concerned the position of the pad upon the shoulder. In general they have had no satisfactory means for positioning, with the result that they are positioned too far forward, or back, or outwardly. This has arisen from the fact that the shoulder has positioned the garment and the shoulder pad has followed the positioning of the garment. It is an object of this invention to make a shoulder pad which will position the garment in true relation to the shoulder so that the garment line will have from all view points a natural semblance.

Another disadvantage of the prior art shoulder pads was the construction of the cloth cover. Such pads were generally composed of a filler or stuffing enclosed within a cloth cover. These covers were frequently difficult to make, including three or even more pieces of cloth that had to be sewed together to conform to the shape of the pad. Such pieces seldom fit the shoulder pad snugly and sometimes caused visible seams to show through silken garments. It is an object of this invention to construct a cover for a shoulder pad out of a single piece of cloth.

In the drawings, wherein like reference characters refer to like parts throughout the several views,

Fig. 1 is a side elevational view of a shoulder pad constructed in accordance with the principles of the invention;

Fig. 2 is a plan view of the shoulder pad of Fig. 1;

Fig. 3 is a transverse or end section on the line 3—3 of Fig. 1;

Fig. 4 is a vertical longitudinal center section on the line 4—4 of Fig. 2;

Fig. 5 is a plan view of the unfolded cover of the shoulder pad.

The numeral 10 indicates a flexible and com-

pressible body which may conveniently be made of sponge rubber. Other materials which are not flexible or not compressible may also be employed: for example, synthetic resins and even light metals. However, the preferred form of the invention is composed of a sponge rubber or similar compressible and flexible body portion and a cover of cloth. The cover is indicated by the numeral 11.

10 The body portion is finned out to an edge 12 of such thickness as to be substantially invisible beneath even silk cloth. Thus, the line of the shoulder pad is molded into the form of the human body. From the edge portion 12 the pad increases in thickness toward a portion 14 which is located above the outer end of the shoulder when the pad is emplaced. However, this increasing of thickness is carried out in a novel and particularly advantageous way. This can best be understood in connection with Fig. 4. In that figure it will be observed that the pad along the line 15 has a curve that conforms to the natural curvature of the shoulder. Therefore, when the pad is fitted over the shoulder it rests snugly thereagainst. The wing portions 16, 17 of the pad fit snugly over the shoulders against the front and back thereof and tend to prevent the pad from being displaced. This is in contradistinction to many prior art shoulder pads which had no means to prevent them from assuming on the shoulder of a particular person an awkward and unnatural position. With this construction of a shoulder pad there is no possibility of the pad being displaced and even natural deformations may be entirely and satisfactorily hidden.

30 Not only is the lower median line 15 of the pad conformed to the natural curvature of the shoulder, but the upper median line 18 is also thus conformed. As line 15 and line 18 both meet at the upper and innermost point 12 and both have a curvature conforming to the natural curvature of the shoulder, the new shoulder line, beneath the cloth of a garment, gives the impression of a natural shoulder line.

40 In order to give a further natural appearance to the cloth of the garment, the shoulder pad is provided with a bulge 20 which is near the upper outer part of the pad. This bulge, being rounded, forms a natural drape in the cloth that lies upon it so that sleeves have a natural drape.

50 The shoulder pad is shield shaped as viewed from above, triangular with one curved side as viewed in elevation, and half moon as viewed in section.

55 Heretofore, the covers of such devices have

been made in several pieces, but I have invented a cover which fits more snugly than prior art covers and which is made of a single piece of cloth. This portion of the invention is shown in plan view in Fig. 5. In that view number 11 indicates a piece of cloth the warp of which runs parallel to one side while the weft runs parallel to the other side. The piece of cloth is square from corner to corner, but is arcuate between corners as indicated at 31. A cut 32 is made on the bias from one corner to a point short of the center and a notch 33 is placed at the outer end of the cut. At the inner end of the cut two short cuts 34, 35 are made approximately along the warp and the weft, respectively, and the edges along those cuts are folded back along the lines 36, 37 and sewed along lines 42-43. The lines 38, 39 are sewed together as far as the center of the pieces of cloth and the abutting hems are sewed, one next the other, along line 44. The surplus cloth between 38 and 39 may then be cut away if desired. The corner 40 is now folded upon corner 33 and the overlapped edges are sewed on lines 41. There is thus formed a pocket with an opening 15. Before the sewing is completed at the point of the shield, as seen in Fig. 2, the ends of the edges of the cut at point 33 are overlapped, as shown in Fig. 2, at 44, so that the stitching closes the pocket. Into this pocket there is placed, through the opening 15, the body shown in Figs. 1 to 4. In this connection the cutting of the cloth on the bias proves to be very important because the cloth of the cover when thus cut yields in those directions which permit the insertion of the body, but does not yield in directions that would cause deformation or distortion of the cloth of the overlying garment. Furthermore, the cloth is thus provided with an elasticity which causes it to conform smoothly to the body after the body has been inserted. Consequently, wrinkles underneath the pad are avoided, obviating irritation to the shoulder of the wearer, and external wrinkling is avoided so that the pad is invisible even under thin cloth.

A particular advantage of this invention is that the shoulder pad fits the shoulder in a stable manner so that the garment must conform to its shape. In this way, the shoulder pad aids in the fitting of the garment and helps to preserve its most desirable conformation and drape.

Another advantage of the invention is that the shoulder pad appears to be natural lacking the bunchiness and misplacement of former shoulder pads.

A further advantage is that the cloth cover and the filler of the shoulder pad conform so that there is an absence of wrinkling of the cloth.

A still further advantage is that the pad can

be made in two complete parts which are assembled after manufacture.

Another advantage is in making the cover of the shoulder pad out of one piece of cloth with a minimum of sewing and a maximum of resiliency.

As many widely different embodiments of the present invention may be made without departing from the spirit and scope thereof, it is to be understood that the invention is not limited to the specific embodiments, except as defined in the appended claims.

What is claimed is:

1. A cover for a shoulder pad consisting of a substantially square piece of cloth having bowed edges and the bias on the diagonal, said cloth being slit from a corner on the bias, straight cut from the end of the slit, and folded and hemmed along the sides of the slit, the cloth being folded on the diagonal normal to the slit, sewed along the edges, and having the hems overlapped and caught at their ends.

2. A cover for a shoulder pad consisting of a substantially square piece of cloth having bowed edges and the bias on the diagonal, said cloth being slit from a corner on the bias, straight cut from the end of the slit, and folded and hemmed along the sides of the slit, folded normal to the slit, and sewed opposite the fold.

3. A cover for a shoulder pad being a generally rectangular piece of cloth folded on the bias along the line joining opposed corners, slit at an angle to the fold from one of the other corners, and sewed along its overlapped edges to form a pocket having an opening made by the slit.

4. The cover of claim 3 in which the slit is partly overlapped and sewed.

5. The cover of claim 4 in which the open part of the slit is hemmed.

6. The cover of claim 3 in which the slit is partly overlapped and sewed together, and partly overlapped and not sewed together.
